(57) **CLAIM**

The ornamental design for a stand lamp, as shown and described.

DESCRIPTION

FIG. 1 is a perspective view of a stand lamp showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another right side elevational view thereof in alternate position.

The portions of the design shown broken away in FIGS. 1, 2, 3, 4, 5, and 8 indicate indeterminate length.
